UNITED STATES PATENT OFFICE.

JAY CHAPIN, OF EDGEWOOD BOROUGH, PENNSYLVANIA, ASSIGNOR TO JAS. H. MATTHEWS & CO., OF PITTSBURGH, PENNSYLVANIA, A CORPORATION OF PENNSYLVANIA.

SILL-SIGN STRUCTURE.

1,079,469.

Specification of Letters Patent.

Patented Nov. 25, 1913.

Application filed May 20, 1912. Serial No. 698,488.

To all whom it may concern:

Be it known that I, JAY CHAPIN, a citizen of the United States, and residing in the borough of Edgewood, in the county of Allegheny and State of Pennsylvania, have invented or discovered new and useful Improvements in Sill-Sign Structures, of which the following is a specification.

My invention consists of new and useful improvements in sill signs which are outdoor signs mounted on the sill or base of a window. Such signs are now commonly made of sheet metal and provided with a wooden backing or supporting structure to provide the required stiffness and prevent denting or bending, and to mount the sign in place.

My object is to provide an inexpensive, easily installed, durable and efficient metal sign-structure which will prevent denting or damaging the sign and will also permit of a sufficient degree of adjustability in mounting to suit the conditions of individual cases. Inasmuch as sill signs are frequently made up at the factory in accordance with measurements furnished by the purchaser and shipped to the latter to be installed by him, who has usually had no previous experience in the work, ease of installation, ability to withstand rough handling and adjustability to overcome errors in measurements are considerations of the very highest importance to both manufacturer and customer. By my method of attaining these objects I am enabled to use a thinner gage of sheet metal than has hitherto been possible which works a substantial saving in copper, the material in general use for that purpose. After installation any desired change in the position or angle of inclination of the sign may be easily accomplished as is evident.

Other novel features of structure and arrangement of parts will appear from the following description.

In the accompanying drawings, Figure 1 is a front elevation of one of my improved signs shown installed at the base of a show-window; Fig. 2 is a vertical section along the line II-II in Fig. 1; Fig. 3 is a perspective of the sheet metal sign proper; Fig. 4 is an enlarged perspective of one of the bottom brackets; Fig. 5 is a section similar to Fig. 2 but showing a modified form of

my sign and Fig. 6 is an enlarged perspective of the top bracket.

The following is a detailed description of the drawings, reference being first had to Figs. 1-4, inclusive. A is the sill or base of a window and B is the wall of the building beneath the same. C is the sign proper, preferably of thin sheet copper and bearing on its outer or exposed face lettering or other advertising matter. In the drawings, I have shown, for the sake of illustration, separate letters 1-1 secured to the sign C by means of bolts 2-2 extending through properly positioned holes 3-3 in the face of sign C and engaged on the back face of said sign by washers and nuts 4-4. The top of said sign C is provided with a longitudinal inwardly extending flange 5. D represents one of a plurality of angularly shaped brackets attached to, as by screws 6-6, and spaced apart along the under face of the sill A. Said brackets D are provided with a shoulder 7 against which the edge of the flange 5 impinges. I prefer to provide a series of notches 8-8 in the edge of flange 5 to respectively embrace the shoulders 7 of the brackets D thus aiding in positioning the upper portion of the sign C. Forward of the shoulders 7 the brackets D extend outwardly as at 9, leaving a sufficient space above them below the sill A to snugly accommodate the flange 5. The outward extensions 9 of the brackets D end in downwardly inclined portions 10 pierced by threaded holes 11 against which the upper portion of the sign C rests and to which it is attached by means of screws 12, which pass through holes 13 in the sign. The angles formed by the portions 9 and 10 of the brackets D fit into the angle between the sign C and its flange 5. It is evident that by advancing or retreating the position of the brackets D on the sill A the top of the sign C may be positioned as desired in relation to the sill A. The brackets D are preferably cast or otherwise formed of bronze or some other ductile metal so that the extensions 10 of said brackets may be bent inwardly or outwardly to obtain the desired inclination in the sign C. I provide the bottom of sign C with an inwardly extending flange 14 which is provided with a series of holes 15-15 preferably slotted transversely of said flange, as shown in Fig. 3. E-E

represent a series of brackets secured to the face of wall B, as by screws 16 and provided at their outer ends with pierced lateral ears 17-17 and a central interposed square boss 18. The flange 14 is secured to said pierced ears 17-17 by means of bolts 19 passing through the slots 15-15. Said bolts extend upwardly being provided with extended washers 20 which bear against the lower face of the flange 14. Said bolts are screwed into nuts 21 which bear against the upper faces of ears 17-17 and are prevented from turning by contact with the flat faces of boss 18 which thus acts as a nut-lock. It is evident that the position of flange 14 may be easily adjusted on the brackets E-E. I prefer to cast or otherwise form the brackets E-E of bronze or some other ductile metal so that the same may be bent, if necessary, to properly position the sign C.

In Fig. 5, I have shown the sign C anchored to the top of the sill A in the manner now usual in the art, the top-flange 5^a being made wider than in the preceding figures, screws 22 being driven down through said flange 5^a into the sill A. It is evident that by varying the position of the screws 22 and regulating the attachment of the bottom flange 14 to the brackets E, the position and inclination of the sign C may be adjusted as desired.

It is evident from the foregoing description that my improved sign structure does away with the use of wooden backing and support with its attendant expense and lack of permanency, provides the necessary stiffness and support to avoid denting or damaging the sign during transportation, installation and use, and also provides means for

ready installation and adjustment by un-skilled labor.

What I desire to claim is:—

1. In a sheet metal sill sign, means for fastening the bottom of said sign, an inwardly extending top flange integral with said sign, and brackets adapted to be secured to the sill and provided with shoulders against which said flange bears and also provided with downwardly extending portions to which said sign is attached, for the purpose described.

2. In a sheet metal sill sign, means for fastening the bottom of said sign to a support, an inwardly extending top flange, having notches in the edge thereof, integral with said sign, and brackets adapted to be secured to the sill and provided with shoulders which seat in said notches and also provided with downwardly extending portions to which said sign is attached.

3. In a sheet metal sill sign, means for fastening the top of said sign to the building, an integral inturned flange at the bottom of said sign provided with a plurality of slots transversely placed, a plurality of brackets fixed to the building and having pierced outer extremities, and bolts engaging said pierced outer extremities and said slots to support the bottom of said sign, said slots permitting the adjustment of the position of said sign.

Signed at Pittsburgh, Pennsylvania, this 16th day of May, 1912.

JAY CHAPIN.
